Fig. 5.

Fig. 4.

FIGURE 1 is a top perspective view taken from the front of a dispensing container embodying my new design;

FIGURE 2 is a top plan thereof;

FIGURE 3 is a side elevation thereof, the opposite side thereof being substantially the same;

FIGURE 4 is a front elevational view thereof; and

FIGURE 5 is a side elevational view thereof with the spout in open position.

The dominant features of my design reside in those portions illustrated in full lines, while the characteristic features thereof reside in a merged unitary relationship between a generally cylindrical container side wall and an integral upwardly swept closed neck portion having convergent inwardly directed side and end walls with exposed aligned bearing openings in said side walls receiv-

ing laterally projecting trunnions on a swingable dispensing spout for supporting the same, all as shown.

I claim:

The ornamental design for a dispensing container, substantially as shown and described.
